UNITED STATES PATENT OFFICE

HUBERT M. GREIST AND HARRY F. THURBER, OF NEW HAVEN, CONNECTICUT, ASSIGNORS TO GREIST MANUFACTURING COMPANY, OF NEW HAVEN, CONNECTICUT, A CORPORATION OF CONNECTICUT

DESIGN FOR A LAMP SHADE

Application filed February 27, 1931. Serial No. 38,856. Term of patent 14 years.

To all whom it may concern:

Be it known that we, HUBERT M. GREIST and HARRY F. THURBER, both citizens of the United States, residing in New Haven, in the county of New Haven and State of Connecticut, have invented a new, original, and ornamental Design for Lamp Shades, of which the following is a specification, when taken in connection with the accompanying drawing.

The figure of the drawing is an elevational

view of a lamp shade embodying our new design.

The shade shown is substantially circular when viewed from the top and has substantially the same appearance regardless of the side from which it is viewed.

We claim:

The ornamental design for a lamp shade substantially as shown and described.

HUBERT M. GREIST.
HARRY F. THURBER.
